UNITED STATES PATENT OFFICE.

LOUIS STOTT, OF HALIFAX, ENGLAND, ASSIGNOR TO SMITH, BULMER AND COMPANY, LIMITED, OF HALIFAX, ENGLAND, A CORPORATION OF GREAT BRITAIN.

DAYLIGHT LAMP FOR COLOR MATCHING, PERCHING, AND SIMILAR PURPOSES.

Application filed October 1, 1925, Serial No. 59,905, and in Great Britain January 19, 1925.

This invention relates to daylight lamps for use in color matching by dyers and others perching or inspecting yarn, cloth, and for other similar purposes, and the object of my invention is an improved construction of this type of lamp whereby the rays of light given off by an electric lamp and radiating upon the sides of the lamp chamber and upon the other deflectors therein, are more or less concentrated and deflected on to the glass panel.

A further object of the invention is to provide a simple and efficient means for ventilating the lamp casing or housing without allowing any of the rays from the lamp therein escaping or passing outward except through the glass panel.

Another object of the invention is to provide a simple and readily adjustable means for varying the relation of the lamp to the glass panel.

I attain these objects by the means illustrated in the accompanying drawing, in which:—

Fig. 1 is a sectional side elevation of my improved daylight lamp.

Fig. 2 is a front elevation partly in section of Fig. 1.

Fig. 3 is a detail showing a sectional view of one of the angular strips or deflectors secured to or formed on the sides of the lamp.

Referring to the drawing. A is the lamp casing angular in shape, and which may be secured to a wall or other support, by screws B passing through brackets C attached to said chamber, or by other suitable means. D is the upper section or portion of the front wall of said casing which may be formed integral with the top or sides of the casing and extends at an approximate angle of 67° to the horizontal. The lower portion of the front wall of the casing includes the glass panel E mounted in a surrounding frame F which is hinged at G to the front wall section D; the said panel when occupying a normal position is at an approximate angle of 135° to the horizontal base of the lamp casing. The hinged panel E is adapted to be moved upon its hinges to afford access to the interior of the casing when desired, and is secured in the closed position by a hasp H, or by any other suitable means. J is an angular reflector one or more of which is or may be attached to the sides of

the lamp chamber and arranged at an approximate angle of 40° to the back of the latter. As shown in Figure 3, the reflectors are of substantially V-shape in transverse cross section.

K is the electric light bulb or lamp of suitable candle power carried by the holder L which is secured to one end of an adjustable tube M movable vertically within a sleeve N secured to a slidable shutter P operating in guides R attached to the top of the chamber A. The flexible conductor S for supplying current to the lamp passes through the tube M and the latter is secured after adjustment, by the screw T. U is a handle for operating the shutter R. V is an air admission tube surrounding an opening W in the floor of the lamp chamber and is surmounted by the double cone shaped cowl X. Y is a conical baffle fixed within the cowl X for preventing any escape of light except through the panel E. Z, Z, are similar means provided in the roof of the chamber A for permitting the escape of hot air therefrom and also preventing the escape of light, as aforesaid.

The internal sides of the lamp chamber and other parts serving as reflectors or deflectors are either burnished or white, the angles of the sides of the lamp chamber and of the parts operating in conjunction therewith being arranged relatively to each other so as to reflect the projecting rays of light from the lamp K in such a manner that they intersect each other eventually concentrating and becoming focused upon the glass panel which is of such a size and arranged at such an angle as to greatly extend the sphere of operations for which daylight lamps are required, as well as their efficiency.

That is the angular faces of the relatively narrow diagonally extending, strip-like reflectors J intercept and re-reflect rays reflected from the casing walls so that all of the light is diffused throughout the chamber and over the inclined glass panel E.

By arranging the reflecting strips J in the particular relation to the walls of the casing and the panel E hereinbefore described, and making said strips of the cross sectional form shown, it has been found possible to diffuse the light uniformly over the entire area of the glass panel.

All of the joints between the several members of the casing are of overlapping con-

struction and the ventilation apertures are of the character before described so that the passage of any rays of light outward from the casing except through the glass panel is prevented.

What I claim as my invention, and desire to secure by Letters Patent, is:—

1. A daylight lamp for the purpose described comprising a casing having a transparent panel in its front wall extending at an obtuse angle to the bottom of the casing, the inner faces of the walls of the casing constituting reflecting surfaces, a source of illumination within the casing, and relatively narrow, elongated, reflectors extending diagonally of the inner faces of the side walls of the casing, for the purpose described.

2. A daylight lamp for the purposes described comprising a casing having a transparent panel in its front wall extending at an obtuse angle to the bottom of the casing, the inner faces of the walls of the casing constituting reflecting surfaces, a source of

illumination within the casing, and relatively narrow, elongated, reflectors of substantially V-shape in transverse cross section extending diagonally of the inner faces of the side walls of the casing with their apices directed inward, for the purpose described.

3. A daylight lamp for the purpose described comprising a casing having ventilation openings in its top and bottom, and its front wall including a transparent panel extending at an obtuse angle to the bottom of the casing and hinged at its forward upper edge to the casing, the inner faces of the walls of the casing constituting reflecting surfaces, a source of illumination within the casing, and relatively narrow, elongated, reflectors extending diagonally of the inner faces of the side walls of the casing from the rear lower corners of the casing to the upper forward corners thereof, for the purpose described.

In testimony whereof I have signed my name to this specification.

LOUIS STOTT.
